[57] CLAIM

The ornamental design of a child's swing, substantially as shown and described.

DESCRIPTION

FIG. 1 is a perspective view of a child's swing embodying my new design,

FIG. 2 is a front elevational view thereof,

FIG. 3 is a top plan view thereof,

FIG. 4 is a rear elevational view thereof, and

FIG. 5 is a bottom plan view thereof.

The side not shown is substantially a mirror image of the side shown.

FIG. 1

FIG. 2

FIG. 3

FIG. 4
